FIG. 1 is a perspective view of a combined bottle and cap showing our new design;

FIG. 2 is a front elevational view;

FIG. 3 is a right elevational view;

FIG. 4 is a rear elevational view;

FIG. 5 is a left elevational view;

FIG. 6 is a top plan view; and,

FIG. 7 is a bottom plan view thereof.

The broken lines immediately adjacent to the shaded areas represent the boundaries of the claimed design, while the other broken lines illustrate environment; none of the broken lines form part of the claimed design. The broken line(s) which define the bounds of the claimed design form no part thereof.
